UNITED STATES PATENT OFFICE.

JAMES FILLMORE COX, OF BAYONNE, NEW JERSEY, ASSIGNOR OF ONE-HALF TO
MATTHEW T. CRONIN, OF BAYONNE, NEW JERSEY.

PIPE OR TUBE BENDING MACHINE.

1,021,450.

Specification of Letters Patent. Patented Mar. 26, 1912.

Original application filed June 3, 1909, Serial No. 499,868. Divided and this application filed March 7, 1910. Serial No. 547,724.

To all whom it may concern:

Be it known that I, JAMES FILLMORE Cox, a citizen of the United States, residing at Bayonne, in the county of Hudson and State of New Jersey, have invented certain new and useful Improvements in Pipe or Tube Bending Machines, of which the following is a specification.

My invention relates to improvements in devices for supporting pipes or tubes while being bent, particularly of that type employing a collapsible plug and chain.

It has for its object more especially to protect the pipe or tube during the bending operation both inside, at, and beyond the bending point or center against rupture or cracking which would occur should any ovalness or flattening be present in the pipe or tube at that point.

20 The nature of the invention consists of certain instrumentalities and features substantially as hereinafter fully disclosed and defined by the claims.

25 In the accompanying drawing illustrating the preferred embodiment of my invention:—Figure 1 is a longitudinal sectional view of the collapsible plug arrangement as used with a revolving ball and flexible chain mechanism and with a mandrel or member 30 55 forming a member of a machine disclosed in a co-pending application, and of which this is a division, filed by me June 3, 1909, Serial No. 499,868. Fig. 1^a is a side elevation of my machine, parts of which are 35 embodied in said co-pending application, showing the practical application of the collapsible plug. Fig. 2 is a broken side view disclosing the operative connection of the plug releasing lever, with the chain, also 40 shown in operative connection with the mandrel or member 55. Fig. 3 is a detailed perspective view of part L⁴¹ as also disclosed in Fig. 1. Fig. 4 is a detailed perspective view of the parts L⁵ and L¹⁰, also shown in 45 Fig. 1, and Fig. 5 is a modification of my invention in longitudinal section for bending tubing of a very thin gage, being employed in direct operative connection with the mandrel or member 55 and displacing in this instance the collapsible plug and chain which are used for the heavier class of work and on the larger pipes and tubing.

In order to successfully bend pipe and

tubing cold it is necessary in some instances to use an inner filling at the bending point, 55 and to protect the pipe or tube to be operated upon at and beyond the bending point or center. There might possibly occur, in the course of bending a slight ovalness or flatness which would extend slightly beyond 60 the center or bending point. It is therefore, necessary to eliminate this flattening in order to retain the perfect symmetry of the outline of the pipe or tube while being operated upon. To this end I provide a steel ball 65 which is composed of two hemi-spherical like parts L² and L³, respectively. Into the center of these is extended a link L⁴ with the end thereof received thereby rounded to the same radius, and a corresponding curvature as to the outside of the steel ball, forming on the end a perfect ball. The members L², L³ are held together by means of a "fillister" head shoulder equipped screw as at L¹. The part L⁴ has a suitable bore or 70 opening for the reception and passage therethrough of the screw L¹. As, in the course of operation the pressure transmitted to the ball tends to cause the latter to roll, such will overcome any tendency to flattening of 75 the pipe or tube. The opposite end of the link L⁴ is connected to the plug by a similar screw L⁸ inserted into the plug and through said end of the link.

80 In order to prevent difficulty in removing the pipe or tubing from the plug, resulting from wedging or sticking of the pipe, I have contrived the following described construction: The member L⁴¹ is arranged centrally of the plug, an opening L²² being provided for the reception of the ball-connecting link L⁴ and an additional opening L²¹ being provided for the reception of the pin L⁸, the link L⁴ extending transversely through said opening L²¹ and allowing of 85 the requisite movement of said link according to the action of the ball. It will be noticed that V-shaped members L⁵, L¹⁰, are arranged upon opposite sides of the member L⁴¹, the latter, itself, being of corresponding shape. The lateral members L⁵, L¹⁰ are provided with dove-tailed grooves L²⁶ which receive correspondingly shaped tongues or ribs L²³ upon the member L⁴¹. 90 95 100

The member L⁴¹ has a square or angular opening L⁹ which receives correspondingly

shaped pins L^7 , L^{11} between which is interposed a spring L^{40} for normally holding the pins under outwardly thrusting pressure for suitable frictional engagement thereof with the members L^6 , L^{10} or notches L^9 therein as seen in Fig. 1. Small steel blocks L^{25} are let into the rear ends of the members L^6 , L^{10} and one also partly into the member L^{41} , being held in place therein by screws L^{24} , the steel blocks being thus controlled in forward movement, which they are designed to have in the course of the bending operation.

It will now be understood that should the pipe or tube have a tendency to stick or bind on the mandrel, a slight movement rearwardly of the pipe or tube will decrease the diameter of the plug and cause the members L^6 , L^{10} to slide rearwardly upon the central member L^{41} , thus bringing the openings L^8 in registration with the opening L^9 , when the pins L^7 , L^{11} will be thrust into the openings L^9 accordingly locking the members L^6 , L^{10} together in collapsed position. The lapsing of the plug, it will be appreciated, will relieve the sticking or binding of the tube upon the plug. The plug may now be readily withdrawn by simply moving it rearwardly, the position of none of the other parts being disturbed.

The plug is suitably held in place in the pipe by means of a mandrel 55 suitably connected thereto, and extending rearwardly and secured to the upper portion of a leg or support F of the machine-frame by means of a lock-nut 31 and a hand-wheel 28, co-operating with said lock-nut and suitably applied to said mandrel, the plug being adapted to be set at the required point without in the tube or pipe for bending, by suitably manipulating said mandrel.

In order to remove the plug, in using it, for instance, in connection with the long lengths of pipe, the hand-wheel 28 is grasped and suitably turned to move the mandrel rearwardly, the pipe or tube thus being released from the plug. In order to re-set the plug the hand-wheel is turned in the reverse direction; the movement of the mandrel being controlled so as to stop the plug at the desired point beyond the center by lock-nuts 31^a and 31^b arranged upon the mandrel just outside of the hand-wheel as clearly disclosed by Fig. 1^a. By suitably manipulating or adjusting the lock-nut 31, the mandrel, with the plug, will be effectively locked in position against any casual movement of the plug in the pipe or tubing.

In operating upon long lengths of pipe or tubing, in which case a mandrel of considerable length is employed, there is a tendency of the mandrel to sag or drop centrally, and in order to overcome this difficulty, I provide a support or rest 21 for the tubing or pipe, which rest or support is designed

to be adjustable to accommodate the different diameters of pipe or tubing. Said support comprises preferably brackets 21^a merged into a lever, the same being suitably fulcrumed in position and bearing a roller 24, said brackets being held together by a connecting rod 25. In order to provide for suitably adjusting and holding the rest or support in adjusted position, I provide in connection therewith a segmental rack 23 engaged by a suitably pivoted pin 22. Still, there are other bends, which are made upon short lengths of pipe, which cannot to advantage, from the stand-point of time and labor saving, be formed by the previous mentioned means of removing the plug. While, however, these means are of advantage and the only means which may be successfully adopted in connection with the longer lengths of pipe or tubing, I am enabled to secure good results in the employment of a flexible connection or chain, such as shown in Fig. 2, which is applied to the forward end of the mandrel 55 by eye-and-pin connection, as indicated at L^{17} , the same being adapted to hold the rear end of the mandrel securely in fastened position. In order to remove the plug with this arrangement I have provided a lever L^{27} as shown, it being suitably fulcrumed, as for instance upon a rod or shaft a which, in practice is supported by the frame of the machine. The lever L^{27} is provided at the upper end with a suitable notch, curvature or indentation for engaging a flexible member or chain connected to the mandrel and designated by the reference-characters L^{14} , L^{15} , L^{17} , L^{19} , and L^{20} . The connecting links of the flexible parts as indicated by L^{18} , etc., are connected to each other by means of pins as L^{15} , each of which acts as a pivot upon which the links swing. Ample space is allowed between the various links to permit freedom of movement thereof.

A lug on the rear end of the member L^{41} of the plug has a passage or bore L^{20} receiving a pin of said chain for effecting connection therebetween. It will be understood that by suitably manipulating the lever L^{27} the required movement is imparted to the plug, as for instance in moving it rearwardly or forwardly, which would have the effect, it is apparent to collapse or reduce and expand the plug, respectively, the purpose of which has been made apparent from the foregoing description. Even this form of collapsible plug and ball joint may be displaced by a more suitable means for operating upon the tubing or pipe, having thinner walls and of softer substance, such as annealed brass tubing and tubing of the less resistive compositions, such as white metal, nickel, etc., and to that end, as suggested by Fig. 3, I effect suitable screw-threaded connection between the forward

end of the mandrel 55 and one end of the rod L³³. This connection is rendered more effective by the application of a lock-nut L³⁸ to the connecting rod L³³ abutting 5 against said end of mandrel. This connecting rod has turned upon its other end a half ball-shaped head L³⁹ over which is fitted a preferably steel sleeve or member L³⁶. Through this sleeve or member L³⁵, which 10 has a suitable recess or bore, is inserted the rod L³⁸, which forms a swivel, upon which it depends for freedom of movement against a hemispherical end or head L³⁹. Rod L³⁸ is threaded at its forward end for application 15 thereto of a nut L³⁴ through which passes a forward connecting rod L^{33a}, upon one end of which is also fitted a hemi-spherical head L³⁶, and which also serves in connection with member L³⁴ as a swivel. The 20 rod L^{33a} projects forwardly and through the member L³¹, which is a similar arrangement to the rod L³⁸ and is secured thereto, upon each side, by means of locking nuts L³², L³⁷, respectively. When this system, 25 as per Fig. 5, is adopted, rod L³¹ takes the relative position, upon the interior of the tube, of the revolving ball L², L³, as in Fig. 1. In the use of this construction it is 30 necessary that the mandrel be stationary, making it necessary to remove the tubing

from the machine after it has been slid off the members L³¹, L³⁵ of Fig. 5. In order to thus slide off the pipe, it is necessary to get power or pressure behind the tubing. This is accomplished by means of the endless carrier 4, Fig. 1 of the machine as shown in my co-pending application before referred to. 35

I claim:—

1. In a machine of the character described, a collapsible plug arrangement, a revolving ball connected thereto, a flexible connection or chain also connected to said plug and a mandrel connected to the aforesaid parts, for bending tubes or pipes. 40
2. In a machine of the character described, the combination of a flexible plug, a rod connection therefor, a revoluble ball connected to said plug and adjusting angular lever for said parts. 45
3. In a machine of the character described, a collapsible plug arrangement, a revolving ball connected thereto, a flexible connection for said plug, and a mandrel connected to said parts. 50

In testimony whereof I affix my signature in presence of two witnesses. 55
